(57) **CLAIM**

The ornamental design for a toy bag as shown and described.

DESCRIPTION

FIG. 1 is a perspective view from above, to the front and to the left side of a first embodiment of the new design for a toy bag;

FIG. 2 is a front view thereof;

FIG. 3 is a rear view thereof;

FIG. 4 is a top plan view thereof;

FIG. 5 is a bottom plan view;

FIG. 6 is a right side view thereof; and,

FIG. 7 is a left side view thereof.

In the drawings, the broken lines are for the purpose of illustrating portions of the article that form no part of the claimed design. Specifically, the evenly dashed broken lines depict portions of the article and form no part of the claim. The dash-dot-dash broken lines shown in FIGS. 1 and 2 depict the bounds of the claim design and form no part of the claim.
